United States Patent Office.

HENRY FEYH, OF COLUMBUS, OHIO, ASSIGNOR TO HIMSELF AND GEORGE T. EMERY.

Letters Patent No. 60,870, dated January 1, 1867; antedated September 13, 1866.

IMPROVEMENT IN STEAM GENERATOR.

The Schedule referred to in these Letters Patent and making part of the same.

TO ALL WHOM IT MAY CONCERN:

Be it known that I, HENRY FEYH, of Columbus, in the county of Franklin, and State of Ohio, have invented an improved Steam Boiler; and I do hereby declare that the following is a full, clear, and exact description thereof, reference being had to the accompanying drawings, making a part of this specification, in which—

Figure 1 is a longitudinal section, taken vertically through the centre of my improved steam boiler.

Figure 2 is a section through the boiler, taken in the horizontal plane indicated by the red line x, x .

Figure 3 is a section taken transversely through the boiler in the plane indicated by red line y, y .

Similar letters of reference indicate corresponding parts in the three figures.

This invention relates to an improved mode of increasing the circulation of water in horizontal or marine boilers for generating steam. It consists in the employment of pipes of different diameters, connected together and exposed to the action of the fire in the fire-box of a boiler, in connection with a chamber, E, or its equivalent, in such manner that by the difference in temperature of the water in said pipes, the small pipes become the steam generators, and the larger pipes the means for feeding water to the small ones from the body of water in the boiler, thus creating a forced circulation and facilitating the conversion of water into steam, as will be hereinafter described.

To enable others skilled in the art to understand my invention, I will describe its construction and operation.

The body of the steam boiler consists of two shells, A B, which form the water space C, and steam space C', as shown in figs. 1 and 2. At the rear end of the fire-box, D, a water back, E, is formed, which leads upward above the crown sheet of said box D, and terminates above the water line, indicated in dotted red lines, figs. 1 and 3. The smoke pipe F may be carried out through the crown sheets of the boiler, as shown in the drawings. The water from the water space C is conducted forward through the chamber E, and through the fire-box D, by means of pipes, a, a , which may be arranged in horizontal or inclined planes. These pipes are secured firmly into the front and rear walls of the chamber E, by means of screw-threads formed on them, or in any other suitable manner. The front ends of the pipes a project through the front wall of the boiler a short distance, and have three-way coupling-boxes, G, suitably secured to them, by means of which they each communicate with two smaller pipes, or tubes, b, b , which pass through the fire-box, and are secured at their rear ends into the back wall of the fire-box, as shown in fig. 1. The coupling-boxes G, which form communications between the pipes a and b at their front ends, may be constructed as shown in the drawings, and secured, steam-tight, to said pipes in any convenient manner. When more than two pipes b are to be used in conjunction with each one of the larger pipes a , the water ways in the couplings G must be increased in number correspondingly. The large and small pipes a, b should be so applied to the boiler that they can be readily removed when occasion requires. When the boiler is properly supplied with water, and a fire is made in the fire-box, the back plate of this box becomes heated, and the water commences to boil in the chamber E, and rises. This chamber is supplied through the smaller tubes b, b , which draw their supply in turn through the large tubes a, a , from the outer or main water space C, the water of which is of a comparatively low temperature. The steam which is thus generated rises in the chamber E, and escapes from it, above the water level, into the steam space C'.

It will be seen from the above description that there are two bodies of water in the boiler, one of which is more directly exposed to the heat than the other; consequently the larger body of water will be rapidly conducted into the chamber containing the smaller and more highly heated body of water, and in the passage through the small pipes b, b , it will be converted into steam.

Having thus described my invention, what I claim as new, and desire to secure by Letters Patent, is—

1. Pipes or tubes leading from the main water chamber, through the fire-box, and communicating with pipes or tubes which also lead through the fire-box, but which enter a water chamber E, that extends above the water level, for producing a forced circulation of water in steam boilers, substantially as described.

2. Pipes or tubes of different diameters, the smaller of which lead through the fire-box and into a chamber that extends above the water level, for conducting the water from the main water chamber of a boiler, substantially as described.
